[57] CLAIM

The ornamental design for an electric drying rack, as shown and described.

DESCRIPTION

FIG. 1 is a perspective view of the electric drying rack in an operative position;

FIG. 2 is an alternate view to FIG. 1, except the drying rack is folded up out of the way on its wall mounting brackets, in which position it is intended to be stored while not in use; FIG. 3 is a right side elevational view of the electric drying rack shown in FIG. 1;

FIG. 4 is a left side elevational view of the electric drying rack shown in FIG. 1;

FIG. 5 is a front elevational view of the electric drying rack shown in FIG. 1;

FIG. 6 is a rear elevational view of the electric drying rack shown in FIG. 1; and,

FIG. 7 is a plan view of the electric drying rack shown in FIG. 1.
